UNITED STATES PATENT OFFICE.

HOWARD PARKER, OF BERLIN, NEW HAMPSHIRE.

BARS FOR USE IN MOVING ROLLS OF PAPER.

Original application filed August 2, 1920, Serial No. 400,601. Divided and this application filed October 22, 1921. Serial No. 509,458.

To all whom it may concern:

Be it known that I, HOWARD PARKER, a citizen of the United States, and a resident of Berlin, county of Coos, State of New Hampshire, have invented certain new and useful Improvements in Bars for Use in Moving Rolls of Paper, of which the following is a specification.

This application is a division of my co-pending application for United States Letters Patent, Serial No. 400,601, filed August 2, 1920.

In moving heavy rolls of paper, such as rolls of newspaper, by means of a crane, or the like, it is customary to insert bars suspended from the crane into the ends of the openings in the paper rolls. Heretofore bars of this sort, owing to the weight of the paper rolls and the leverage exerted frequently resulted in mutilation of the paper about the openings receiving the bars, or in the breaking down of the cores where the paper is wound on such cores. It is the object of the present invention to overcome this difficulty and to this end I provide bars by means of which rolls of paper may be lifted without danger of injuring the same.

In the accompanying drawings—

Figure 1 is a view showing the manner in which the bars of the present invention are employed for connecting a roll of paper to a crane; and

Figure 2 is an enlarged view showing one of the bars within a paper core on which a roll of paper or the like is wound.

Referring to the drawings in detail, *a* denotes the boom of the crane or the like, and *b* the chains or ropes by which the roll of paper *c* is suspended from the boom. In

the present instance, the roll of paper *c* is shown wound on a core *x*. The boom, chains, and roll of paper are illustrated in dotted lines, since they are shown merely to indicate one manner in which the bars of the present invention may be employed. 45

Each of the bars of the present invention is provided with a relatively long spindle 10 entering the opening of the core *x* of the roll of paper. The opposite ends of each spindle are similarly tapered in opposite 50 directions, as at 20, 30, so that relatively long substantially parallel bearing surfaces between the core wall and the spindle are obtained thereby greatly reducing the likelihood of cracking or breaking down the 55 wall of the opening. On the protruding end of each bar is a grooved head 32 about which the chains *b* are adapted to pass. The spindle portion of the bar is considerably longer than the protruding end so as to reduce 60 leverage.

I claim as my invention:—

1. A pair of members adapted to be inserted into the opposite ends of the opening in a paper roll and each comprising a spindle 65 having its ends similarly tapered in opposite directions, and means protruding beyond the roll for attachment to a suitable supporting member.

2. A pair of members adapted to be inserted into the opposite ends of the opening in a paper roll and each comprising a relatively long spindle having its ends similarly tapered in opposite directions and means protruding a relatively short distance beyond the roll for attachment to a suitable 75 supporting member.

HOWARD PARKER.
